UNITED STATES PATENT OFFICE.

WILLIAM F. BROWN, OF BROOKLYN, NEW YORK, ASSIGNOR TO THE BIGELOW CARPET COMPANY, OF CLINTON, MASSACHUSETTS.

DESIGN FOR A CARPET.

SPECIFICATION forming part of Design No. 19,841, dated October 8, 1889.

Application filed September 10, 1889. Serial No. 323,561. Term of patent 3½ years.

To all whom it may concern:

Be it known that I, WILLIAM F. BROWN, a subject of the Queen of Great Britain, residing in Brooklyn, Kings county, New York, 5 have invented a new and original Design for Carpets, of which the following is a specification, reference being had to the accompanying photograph, which forms a part of the same.

10 The invention relates to a design to be worked into or upon surfaces, such as carpets or similar fabrics; and it consists in the novel configuration and grouping of figures herein specifically shown and claimed.

15 The accompanying photograph is a face view of a carpet showing my new design.

My design consists of the body A and the border B. The body A is composed of large figures having somewhat flower-shaped outlines containing flower and leaf forms and other ornaments of various characters. The

border B has an inner margin composed of a row of ornaments and an outer margin having a wide band of flower and leaf forms and smaller ornaments. Between the margins 25 are arranged large figures having somewhat flower-shaped outlines and containing flower and leaf forms and other ornaments of various characters.

What I claim, and desire to secure by Letters Patent, is—

1. A design for carpets, consisting of the body A, substantially as shown.

2. A design for carpets, consisting of the border B, substantially as shown.

3. A design for carpets, consisting of the body A and the border B, substantially as shown. 35

WILLIAM F. BROWN.
